UNITED STATES PATENT OFFICE.

FREDERICK T. KITCHEN, OF NEW YORK, N. Y., ASSIGNOR TO GOLD CAR HEATING & LIGHTING COMPANY, OF NEW YORK, N. Y., A CORPORATION OF NEW YORK.

ELECTRICAL HEATER.

1,147,952.

Specification of Letters Patent. Patented July 27, 1915.

Application filed August 28, 1914. Serial No. 859,054.

To all whom it may concern:

Be it known that I, FREDERICK T. KITCHEN, a citizen of the United States of America, residing in West New Brighton, Staten Island, in the borough of Richmond, city and State of New York, have invented certain new and useful Improvements in Electrical Heaters, of which the following is a specification.

10 My invention relates to electrical heaters particularly of the type used in heating railway passenger cars, trolley cars, etc., and has for its object to provide a heater of such type which shall be simple and economical in construction, and will permit of the ready removal of a heating unit from the casing and the insertion of a fresh heating unit therein without withdrawing the car from service and consequently without 15 the delay usually attendant upon this operation and the loss of service of the car and expense connected therewith.

My invention consists in a heating unit which is capable of easy insertion and removal from the casing and wherein the act of insertion or removal causes the opening or closing of the heating circuit.

A desirable form in which my invention may be embodied is illustrated in the accompanying drawing wherein—

Figure 1 is a top view of a portion of a casing illustrating one heating unit in place in accordance with my invention. Fig. 2 is a cross section on the line 2—2 Fig. 1.

35 My invention is illustrated in connection with a heater of the type wherein a core A is provided which is formed of insulating material usually such as porcelain, and has a spiral groove which receives the helically coiled resistance wire B which is the heating element. The heater is provided with a central core C usually a metallic rod which fulfills the function of holding the heater together when such function is desired and 40 when the heater is used in multiple provides a convenient return wire. Such multiple arrangement is illustrated in the accompanying drawings, but my invention is equally applicable to a heater connected in 45 series.

My invention comprises the use of supports which are located within the casing and which receive and hold the heating units both by friction and preferably also by

spring action. These supports or brackets 55 are in electrical connection with the feed and return wires respectively and as the heating unit is inserted in them contact is made between the said connections to the feed and return wires and like connections to the 60 heating wires on the core, whereby the insertion of the heating unit closes the circuit through the resistance wire. The particular manner in which the invention is constructed as illustrated comprises a spring 65 clip or yoke D for each of the heating units. The heater herein illustrated is adapted to receive two heating units. These are identical in construction and are connected in the same manner to the electrical conductors, 70 and may be used one at a time or both. The connection of only one of them will be described and this description will also apply to the other one. This yoke D has means whereby when the heating unit is inserted 75 therein connection will be made between the main wire and a terminal of the heating wire on the heating unit. A convenient way of making such connection is by forming the yoke D of conducting material such as 80 spring brass and by having an eye E therein to which the feed wire F may be attached. The heating unit, which as a whole I shall designate as G is provided at one end with a terminal for the heating wire B, and this 85 terminal may well be in the form of a band H which surrounds the heating unit adjacent the end thereof and is electrically connected to the resistance wire B at I. This connection I will obviously be made in such 90 manner as to permit the heating unit to be inserted when a band H is employed with any portion of the band in contact with the spring yoke D so that no care need be exercised in inserting the same. Obviously if 95 a different kind of terminal to the resistance wire than the band H were employed, and if a different kind of terminal than the spring yoke itself to the feed wire F were employed, care might have to be employed 100 in assembling to bring the respective terminals to a contact. The resistance wire B, in the construction shown, is connected at its opposite end to the rod C in a suitable manner, so that the current shall be returned 105 therethrough. One manner of effecting such connection is by a band J upon the end of the rod to which the resistance wire is con-

nected electrically at K. A washer or disk L of conducting material is forced into electrical connection with the said band J by a nut c upon the rod C. At the opposite end of the rod C a boss or stud M of conducting material is secured thereon and this is preferably made round and is adapted to pass within a spring clip or yoke N which is similar to the yoke D and has a connection at O for the return wire P.

By means of the foregoing the insertion of the heating unit G within the spring clips Q, N and D would cause connection to be made with the feed and return wires F and P through the terminals of the resistance wire B at H and M. I have illustrated a spring clip or yoke Q which is situated at the opposite end of the heating unit and is well adapted to support that end and permit the easy insertion of the heating unit therein and its removal therefrom when desired. In the construction shown this spring support Q need not be in electrical circuit. If however, the heating unit were connected in series the spring support Q would be a duplicate of support D and would furnish connection to the return wire.

The heater supports herein illustrated are connected to and supported upon the casing. The casing herein illustrated is intended for use beneath the removable seat of a passenger car. It is not herein claimed as it is the subject matter of a separate application for patent, Serial No. 861,373, filed by A. O. Bailey, September 12, 1914. It has a back plate R to which the end blocks S, S¹ are secured as by the bolts shown and these end blocks support the said spring yokes D, N and Q in some suitable manner for instance, by the bolts illustrated. The said end blocks are preferably formed of insulating material such as porcelain. They are supported upon the frames T, T¹ in a suitable manner as for instance, by straps U which pass beneath the casing and above the frames. The casing is made in two halves of which the base or bottom R supports the heating units and the top or cover V supports a shield or baffle plate W which is designed to reflect the heat away from the seat S. The end plates of the casing are removed in the drawings. The invention is not limited in its employment to a casing of this character although it is well adapted to use with the same. It may equally well be used in connection with the ordinary type of casing having a solid back and a perforated cover plate which is usually located behind the riser of the ordinary lengthwise seat of trolley cars.

The end blocks are not claimed herein but form the subject of a separate application Serial No. 855,351, filed by A. O. Bailey, August 6, 1914.

Although I have described in some detail the construction in connection with which I have illustrated my invention I do not wish it to be understood that the invention is limited to the precise construction shown as its construction may be changed and different ways of getting the electric current through the heating unit may be provided, or different kinds of casings employed all within the limits of the appended claims.

What is claimed is:—

1. In an electric heater having a casing and a removable cover, and a heater unit comprising a non-conducting core and a resistance wire, an annular band of conducting metal surrounding said core adjacent the end thereof and electrically connected to said resistance wire, spring retaining yokes inside of said casing and between the ends thereof, and opening toward the cover and adapted to receive and support said heater unit and permit its removal, whereby said heater unit may be removed through an opening in a side of said casing upon the removal of the cover, one of said retaining yokes being electrically connected to a main wire whereby the heater unit may be inserted in any position and close the circuit through said heater.

2. In an electric heater having a casing and a removable cover, and a heater unit comprising a non-conducting core and a resistance wire, and a conducting rod passing through said core and electrically connected at one end to said resistance wire, an annular band of conducting metal surrounding said core adjacent the opposite end thereof and electrically connected to said resistance wire, an annular stud projecting from the core inside of said band and insulated therefrom and electrically connected to said rod, spring retaining yokes for the respective ends of said heater and for said stud, all said yokes located inside of said casing and between the ends thereof and opening toward the cover and adapted to receive and support said heater unit and permit its removal, whereby said heater unit may be removed through an opening in a side of said casing upon the removal of the cover, one of said retaining yokes and the said stud yoke being connected respectively to feed and return wires, whereby the heater unit may be inserted in said yokes in any position and close the circuit through said heater.

3. In an electric heater having a casing, a removable cover, and a heater unit, means for supporting said heater unit within the casing comprising spring retaining yokes, adapted to receive and hold said heater unit, said yokes being located inside of said casing and between the ends thereof and opening toward the said cover and adapted to receive and support said heater unit and

5 permit its removal therefrom whereby said heater unit may be removed through an opening in a side of said casing upon the removal of the cover, said heater unit having a resistance wire thereon and an annular band of conducting metal at one end thereof and in electrical connection with said resistance wire and said spring yoke having its end bent into an eye adapted to
10 receive and retain an electrical wire where-

by said heater unit may be inserted in said yoke in any position and close the circuit.

In witness whereof, I have hereunto signed my name in the presence of two subscribing witnesses.

FREDERICK T. KITCHEN.
